UNITED STATES PATENT OFFICE

138,593

DESIGN FOR A BOTTLE WARMER

John H. Gulick, Garfield Heights, Ohio

Application March 11, 1944, Serial No. 112,862

Term of patent 14 years

(Cl. D83—8)

To all whom it may concern:

Be it known that I, John H. Gulick, a citizen of the United States, residing at Garfield Heights, county of Cuyahoga, and State of Ohio, have invented a new, original, and ornamental Design for a Bottle Warmer, of which the following is a specification, reference being had to the accompanying drawing, forming a part thereof.

Fig. 1 is a side elevational view of the bottle warmer, showing my new design;

Fig. 2 is a top plan view of the bottle warmer; and

Fig. 3 is a cross-sectional view, taken on the line 3—3 of Fig. 2.

The characteristic features of the design reside in a bottle warmer of the specific configuration shown.

I claim:

The ornamental design for a bottle warmer, as shown and described.

JOHN H. GULICK.
